DESIGN FOR A RUG

William W. Robinson, Memphis, Tenn., assignor to McCallum & Robinson, Inc., Memphis,
Tenn., a corporation of Tennessee

Application November 19, 1936, Serial No. 66,021

Term of patent 14 years

To all whom it may concern:

Be it known that I, William W. Robinson, a citizen of the United States, residing in Memphis, in the county of Shelby and State of Tennessee, have invented a new, original, and ornamental Design for a Rug, of which the following is a specification, reference being had to the accompanying drawings, forming part thereof, in which:

I claim:

The ornamental design for a rug, as shown, and described.

WILLIAM W. ROBINSON.
